UNITED STATES PATENT OFFICE

THOMAS C. WILSON, OF BROOKLYN, NEW YORK

TUBE CLEANER

Application filed May 12, 1927. Serial No. 190,790.

The device, the subject of this invention, is a brush intended for cleaning the tubes of a boiler and the objects of the invention are to provide a brush that will have a longer wear; that will more readily accommodate itself to the inner walls of the tube to be cleaned and that may go readily up past the return bends usually found as a fitting at the back end of boiler tubes.

Another object of the invention is to provide means whereby a brush of particularly stiff bristles may be employed without fear of cutting the interiors of the tubes to a harmful extent, or, because of the width of the brush, crushing the bristles to such a degree as to make them inoperative.

The following is what I consider the best means of carrying out my invention and the accompanying drawing should be referred to for a complete understanding of the specification.

In the drawing:

Fig. 1 shows a sectional view on the line 25 1—1 of Fig. 4.

Fig. 2 shows a sectional view of the body of my brush slightly modified.

Fig. 3 is a sectional view of the movable member.

Fig. 4 is a longitudinal sectional view of my brush.

Fig. 5 is a side elevation of the movable member.

Fig. 6 is a side elevation of a complete assembly.

Similar reference numerals indicate like parts in all the figures where they appear.

The body member of my brush as well as the insert member may be formed of any suitable material. The body member is first formed as a solid cylindrical member, but as shown in the figures I provide a longitudinal channel through the body member for a purpose that shall appear later and a body member having such a longitudinal channel is shown at 1.

The channel which is indicated at 2 extends into the body member for about one-half of the diameter of the body member and 50 is provided with a continuing recess of any

desired shape as shown at 3 in Fig. 1 and 4 in Fig. 2.

Into the recess or channel 2 I fit a bar or insert 5. This bar which is shown in side elevation in Fig. 5 has its ends reduced as shown at 6 and 7 and as shown in Fig. 3 the bar 5 is provided with a recess 8.

Referring back to Figs. 1 and 2, it will be noted that I produce a plurality of holes extending from the outer edges of the member 60 1 and terminating in the recess of groove 3 or 4 and it will be noted that these holes or passages as I may call them, may be of uniform diameter for their entire length as shown at 9 and 10 in Fig. 1 or may be formed 65 with a passage of reduced diameter at their inner end as shown at 11 and 12 in Fig. 2.

In the bar 5 I also produce a plurality of holes or passages as shown at 13 and 14, each of these holes or passages terminating in the recess 8 shown in the under side of the bar 5. It is my intention that bristles of a suitable 70 nature, such for instance as steel wire bristles, be inserted into all of the passages or perforations 9—10, 11—12, 13—14 and when so 75 inserted and with the member 5 in place in the channel 2 the bristle will project from the member 1 at approximately equal distances apart.

To secure the bristles 15 in the member 5, a tie wire 16 is passed through the bristles and the bristles are drawn down to the bottom of the slot 8, thereafter and with the bristles and tie wire in place, the slot 8 is filled with solder or any other suitable supporting 80 material.

The bristles 17 and 18 are secured in their holes or passages 9 and 10 by tie wires as shown at 19 and 20 and thereafter the extension groove or recess 3 or 4 is filled with 85 solder as is the recess 8.

The ends of the member 1 beyond the bristle receiving portion is screw threaded as shown at 21 and 22 and upon each end I place a cap 23 or 24, the cap 24 having a projection 90 25 for the reception of the operating rod, if such is used.

Adjacent to the screw threaded portions 21 and 22 and within the member 1 I produce recesses as shown at 26 and 27 and in each of 100

these recesses I place a spring 28 or 29. One end of the spring rests against the inner surface of the adjacent cap and the other end of the spring rests against the adjacent projection 6 or 7 of the member 5 and in so doing urges the member 5 outward to the full extent allowed by the caps and at the same time provides a resilient support resisting as much as desired the movement inward of the member 10 5 and the bristles carried thereby.

It will be understood that the caps 23 and 24 are interchangeable, thus preventing distortion of the bristles by uneven wear. It will also be understood that a greater or lesser 15 number of bristle tufts than that shown may be employed and particular attention is called to the fact that the bristles of each series are arranged in staggered relation to the bristles of the next series.

20 The ability of the bar 5 to recede against the spring pressure of the springs 27 and 28 makes it possible for this brush to pass readily around close radial bends. It also assures a cleaning effort even after the brush becomes 25 worn to an extent that would make the rigid type of brush useless. The life of this brush is therefore longer than the ordinary type of brush and the cleaning more uniform throughout its life.

30 The size of all parts may be changed and other modifications may be made within the scope of the appended claims, without departing from the principle or sacrificing the advantages of the invention.

35 Having carefully and fully described my invention, what I claim and desire to obtain is:—

1. A brush having a body member provided with a recess, a movable member retained partially within said recess therein, a plurality of tufts of bristles in alignment in both said body member and in said movable member and resilient means for urging said movable member outward.

40 2. A brush comprising an elongated cylindrical body member provided with a longitudinal recess and a deeper recess at each end of said longitudinal recess, bristles in said cylindrical body, bristles in said bar, and 45 springs one in each said deeper recess and adapted to engage one at each end of said bar for urging said bar outward, each end of said bar being slightly reduced, and a cap at each end of said cylindrical member for retaining said bar and engaging said bar upon its reduced portion.

50 Signed at the city, county and State of New York, this 19th day of November, 1926.

THOMAS C. WILSON.
